UNITED STATES PATENT OFFICE.

ERIK A. LUNDVALL, OF JERSEY CITY, NEW JERSEY, ASSIGNOR TO THE KEYSTONE WATCH CASE COMPANY, OF PHILADELPHIA, PENNSYLVANIA, A CORPORATION OF PENNSYLVANIA.

WATCH-MOVEMENT.

1,084,215.

Specification of Letters Patent. Patented Jan. 13, 1914.

Application filed September 9, 1912. Serial No. 719,326.

To all whom it may concern:

Be it known that I, ERIK A. LUNDVALL, a citizen of the United States, and a resident of Jersey City, in the county of Hudson and State of New Jersey, have made and invented certain new and useful Improvements in Watch-Movements, of which the following is a specification.

My invention relates to an improvement 10 in watch movements, and more particularly to that style or type commonly known and referred to as stem winding and setting movements, the invention being directed to the mechanism for holding the several parts 15 in their winding and setting adjustments, the object thereof being to provide means for accomplishing this end which shall be simple and cheap to construct, effective in operation, and easily, readily and quickly 20 assembled.

A further object of the invention is to provide a single piece spring, which will effectually operate to hold the pendant and shipping levers in their several adjustments 25 or positions, and with these and other ends in view the invention consists in certain novel features of construction and combinations of parts as will be hereinafter fully described and pointed out in the claims.

30 In the accompanying drawings: Figure 1 is a view of a part of a watch movement showing the several parts in their proper relative positions for setting the movement; Fig. 2 is a view thereof showing the several 35 parts in position for winding the movement.

Referring to the drawings, 3 represents the dial plate with which is associated the winding arbor 4, having mounted thereon the winding pinion 5 and clutch 6, the latter 40 being provided with ratchet teeth 7 at its upper end, and teeth 8 at its lower end, to engage respectively the teeth on the winding pinion 5 and the setting pinion 9, the clutch being provided with a circumferential 45 groove 10; all of these parts are constructed and arranged and operate in the usual way, and form no part of the present invention.

To the dial plate 3 is pivoted at 11 the pendant lever 12, this lever being somewhat 50 Z shaped, the one end 13 engaging the winding stem or arbor, and the other extreme end being preferably rounded as illustrated at 14, to engage with the pendant lever spring, as hereinafter described, the pivot 11 being 55 located at one of the angles of the lever, the

other angle 15 of the lever being formed or shaped to ride and rest upon the shipping lever 16, when the several parts are in the setting position as illustrated in Fig. 1. This shipping lever 16 is pivoted at 17 to 60 the dial plate 3, the longer arm thereof engaging in the circumferential groove 10 of the clutch, and the shorter arm engaging with the pendant lever spring, whereby the clutch 6 will be raised into the normal or 65 winding position, as illustrated in Fig. 2, as will be hereinafter more particularly described.

The shipping lever 16, on its longer arm, is provided with a cam or inclined face 18, 70 and flat shoulder 19, with which engages the angle 15 of the pendant lever 12 when the parts are shifted from the winding to the setting position, the angle of the lever 12 riding up the inclined face 18 and over and 75 upon the shoulder 19 as illustrated in Fig. 1, the parts being held in this position by means of the pendant lever spring herein-after referred to.

To the dial plate 3 is secured a pendant 80 lever spring by means of a screw 20, this spring being preferably made of wire and shaped as illustrated, that is formed with an arm 21, the extreme end 22 of which bears against the shorter arm 23 of the shipping lever 16, the opposite end of the arm being looped as illustrated at 24, the tendency of the arm 21 being to lower the shorter arm 23 of the shipping lever 16 and to raise the longer arm, whereby to normally hold 90 the clutch 6 in engagement with the winding pinion 5. Beyond the retaining screw 20 is located the other arm 24 of the spring bearing against a stud 25 formed on or secured to the dial plate 3, the end of this arm 95 25 being curved as illustrated at 26, the extreme end 27 thereof bearing against the flange 28 of the dial plate 3, and the curved portion 26 bearing or impinging against the rounded end 14 of the pendant lever 12. 100

When the winding stem or arbor is in its normal or winding position, as illustrated in Fig. 2, the curved portion 26 of the spring 24 will hold the end 14 of the pendant lever 12 against the flange 28 of the 105 plate 3, the arm 21 of the spring bearing on the end 23 of the shipping lever, tending to hold the clutch 6 in engagement with the winding pinion 5. When, however, the winding stem or arbor is pulled outwardly 110

as illustrated in Fig. 1, the angle 15 of the pendant lever 12 will ride up the inclined face 18 of the shipping lever, forcing that respective end of the latter downwardly, until said pendant lever rests upon the shoulder 19, and forcing the clutch 6 downwardly into engagement with the setting pinion 9, a tension being placed on the arm 21 of the spring. At the same time the 10 rounded end 14 of the pendant lever 12 is pressed inwardly or in a direction away from the pivot 11 by the curved portion 26 of the spring, until said rounded end 14 occupies a position on the opposite side of the 15 center of the loop of the spring, the tendency of this loop or curved portion of the spring being to hold the pendant lever in engagement with the shipping lever, and the parts in their setting position. When the winding 20 stem or arbor is then pushed inwardly, the rounded end 14 of the pendant lever is carried off of the shoulder 19 of the shipping lever, and the rounded end 14 thereof held against the flange 28 of the dial plate 3, the 25 tension of the spring 21 lowering the arm 23 of the shipping lever, and raising the opposite end until the clutch again engages the winding pinion 5, as illustrated in Fig. 2.

From the foregoing it will be seen that the 30 one spring, made of a single piece of round wire, operates to hold both the pendant and shipping levers in their respective positions, that is in their winding and setting positions, and in practice operates to change the 35 positions of the levers with a positive click.

The parts so constructed and arranged are cheap to manufacture and may be easily and readily assembled.

What I claim is:

40 1. In a watch movement, the combination with a dial plate formed with a peripheral flange, of a pendant lever pivoted to said plate, a shipping lever pivoted to said dial plate, and a spring secured to the dial plate and constructed of a single piece of metal, one arm of said spring bearing against said

shipping lever, and the end of the other arm of said spring being bent into the form of a loop, the extreme end thereof bearing against said peripheral flange on the dial 50 plate, one arm of said pendant lever engaging the loop portion of said spring, substantially as shown and described.

2. In a watch movement, the combination with a dial plate formed with a peripheral flange, of a pendant and shipping lever, each pivoted to the dial plate, a spring constructed of a single piece of metal and secured about midway its length to said dial plate, one end of said spring bearing against one 60 end of the shipping lever, and the other end of said spring being bent into the form of a loop, the extreme end of which bears against the peripheral flange on the dial plate, the looped portion of the spring bearing against 65 one end of the pendant lever, substantially as described.

3. In a watch movement, the combination with a dial plate formed with a peripheral flange, of a pendant and shipping lever, 70 each pivoted to the dial plate, a spring constructed of a single piece of wire and secured about midway its length to said dial plate, the end of one arm of said spring engaging one end of said shipping lever, the 75 opposite end of the spring being bent into the form of a loop, the extreme end of which bears against the peripheral flange on the dial plate, said pendant lever having the extreme end of one of its arms engaging 80 the looped portion of the spring, and a pin secured to said dial plate and against which rests the spring between the looped end thereof and the point where it is secured to the dial plate, substantially as described. 85

Signed at Jersey City, in the county of Hudson, and State of New Jersey, this 6th day of September, A. D. 1912.

ERIK A. LUNDVALL,
